FASTENING DEVICE

Heinrich Clasen, Brandholzweg,
Burg in Dithmarschen, Germany

Filed Jan. 10, 1966, Ser. No. 519,700

Claims priority, application Germany, Jan. 27, 1965,
C 34,960

1 Claim. (Cl. 24—117)

The present invention relates to a fastening device. More specifically, the invention relates to a fastening device for frictionally holding filaments. Still more specifically, the invention relates to a fastening device for fastening shoe laces.

The conventional way of tying shoe laces by knotting them is relatively difficult, particularly if the laces are to be tied in the dark, by persons who are handicapped or infirm, or by small children. This is so because tying of a knot or a bow requires considerable coordination which in small children is not yet present, and which the infirm or handicapped persons may have largely lost.

Ways and means have been sought to provide relief in such circumstances, and various suggestions have been made to overcome the problem. For example, fastening elements have been provided with openings through which the ends of the shoe laces can be placed and with slots, for instance tapering slots, in which the ends of the shoe laces are then frictionally secured. However, this still requires a fair amount of coordination and skill and, moreover, the shoe laces are subject to considerable wear and tear at the identical point in each tying operation. Also, each end of the lace must be secured separately with these devices, and this of course results in an increase in the difficulties, rather than in a decrease. In another arrangement which is known in the prior art, the shoe laces are clamped. The drawback there is that the device must exert a relatively strong pressure to maintain the shoe laces in the holding device against displacement. By the same token, a relatively great amount of strength is required on the part of the user to overcome this pressure when inserting and withdrawing the shoe lace ends from the holding device. Moreover, such devices generally cannot be operated by persons who have, for instance, only one arm or have lost the use of some fingers.

It is therefore a general object of the present invention to provide a fastening device which will overcome the above-mentioned drawbacks.

A more specific object of the present invention is to provide a fastening device which requires for its use but little manual skill and coordination.

A further object of the invention is to provide a fastening device which can be operated even in the dark, by the handicapped and infirm, and by small children.

A concomitant object of the invention is to provide a fastening device which is simple and inexpensive to manufacture.

Yet an additional object of the invention is to provide a fastening device as described hereabove which can be easily released, and in which the shoe laces or other filamentary material with which the device is used are not subject to any significant amount of wear.

In accordance with one feature of the present invention I therefore provide a fastening device for frictionally holding filaments, particularly for tying shoe laces. This tying device may comprise a winged member having an apertured hub portion and a plurality of circumferentially spaced wings on said hub portion. The member may be further provided with respective recesses between adjacent ones of these wings so that, after a portion of said filamentary material is passed through the apertured hub portion from one to the other side of the member, that portion of the material which extends beyond the other

2

side can thereupon be inserted into the respective recesses and guided along opposite sides of consecutive ones of the wings.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a perspective view of one embodiment of the invention;

FIG. 2 is a section through a modified embodiment of the invention;

FIG. 3 is a perspective view of still a further modified embodiment; and

FIG. 4 is a section taken on the line IV—IV of FIG. 3.

Discussing now the drawing in detail, and firstly FIG. 1 thereof, it will be seen that there is provided a winged member 1, having a hub portion provided with an aperture 2. Spaced circumferentially about the member 1 and separating adjacent ones of the wings provided thereon are four recesses 3, 4, 5 and 6. These recesses thus define the wings 3', 4', 5' and 6'. The recesses are so arranged that two recesses are always located opposite one another. Preferably, the recesses taper inwardly in the direction towards the hub portion, that is towards the aperture 2. The ends 9 and 10 of a shoe lace are inserted from one to the other side of the member 1 and a knot (not numbered) is tied in them so that accidental withdrawal of the ends 9, 10 through the aperture 2 is prevented.

In operation of the novel tying device, the two ends 9, 10 together are first inserted into the one of the recesses, for example the recess 3, passed along the underside of the wing 3' into the recess 4, and from there along the upper side of the wing 4' into the recess 5. This is repeated until the ends 9, 10 again are received in the recess 3. Thereafter, the ends 9, 10 are given a left turn underneath the member 1 and are thus frictionally held between the underside of member 1 and the upper side of an associated shoe.

Advantageously, the device will be positioned in such a way that the recess with which the tying action begins— and in which it subsequently ends—points towards the toe of the respective shoe. The ends 9, 10 will then be pulled in the direction of the toe after they have been given the left turn underneath the member 1.

To release the ends 9, 10 it is simply necessary to first reverse the left turn by describing a right turn, and then to pull the ends 9, 10 of the lace in the direction towards the toe of the respective shoe. Thereby the shoe lace ends will unwind from the member 1 by first sliding over the upper side of one of the wings, then over the lower side of the next, and so on until they have been completely removed from the member 1 which, during this process, performs a wobbling rotation.

As is evident from FIG. 2, the member 1 may be of more than one cross sectional configuration. In FIG. 1 it is shown as having a flat underside and a convex upper side, and this may also be reversed and the upper be made flat, with the underside convex. However, as shown in FIG. 2 the member 1 may also have a lenticular shape, that is it may be bi-convex in that both the upper and the underside are convexly shaped. This is of advantage in that it enables an easier sliding movement of the ends 9, 10 over the respective wings.

Yet a further embodiment is shown in FIGS. 3 and 4 and it will be seen that in FIG. 3 the member is designated with reference numeral 14 and is shown as having three recesses 11, 12 and 13 which are circumferentially spaced at identical intervals. The upper side of each of

the wings carries an upwardly extending projection; respectively designated 15, 16 and 17 and each of these projections 15-17 is provided in its radially outwardly directed lateral face with a recess so as to provide an overhanging edge 19 which defines a groove with the surface of the respective wing. The hub portion is again provided with an opening, here designated with reference numeral 18.

Operation of the device of FIG. 3, which is shown in section in FIG. 4, is the same as that described with reference to FIG. 1. The only exception is that, rather than simply passing over the upper side of the respective wings, the ends 9, 10 of the shoe lace are placed into the grooves defined by the overhanging projections 19, and are therefore firmly held against undesired sliding-off.

Various different materials are suitable for the novel tying device, and synthetic plastic material is advantageously used. Also, the basic device can be covered with various materials, such as plastic, foil, leather and similar materials, if this should be considered desirable to enhance its appearance or, for instance, to provide a smoother surface.

The invention has been described herebefore with reference to a tying device for shoe laces. However, its range of applicability is by no means exhausted in this description. For example, this device can be used as a closure for bags utilizing draw strings, which latter can be placed around the device in the same manner as shoe laces. Again the device can be used as a tying arrangement for temporarily separating or securing the many small-gauge wires of multistrand communication cables. In such a case, the device may be provided with more than one aperture in the hub portion thereof, one for each wire or group of wires, and this possibility, as well as various other possibilities which will offer themselves readily to a person skilled in the art, is intended to be encompassed in the protection sought.

It will be understood that each of the elements described above, or two or more together, may also find a useful application in other types of fastening devices differing from the types described above.

While the invention has been illustrated and described as embodied in a fastening device, it is not intended to be limited to the details shown, since various modifications and structural changes may be made without de-

parting in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claim:

What is claimed as new and desired to be secured by Letters Patent is:

A fastening device for frictionally holding filaments, particularly for tying shoe laces, comprising a winged member having two convexly shaped faces, an apertured hub portion at the thicker medial portion of said member, and a plurality of spaced wings extending outwardly from said hub portion toward the thinner portion of said member and defining between themselves inwardly tapered recesses so that, when filamentary material is passed through said apertured hub portion from one to the other face of said member, that length of said material which extends beyond said other face can thereupon be threaded through said recesses and along opposite sides of said wings, said wings comprising two pairs of wings with the wings of each pair being diametrically opposite one another and with all of said wings being equidistantly spaced about the circumference of said hub portion.
